DEVICE TO GASIFY FUEL OIL

Arthur J. Behling, Chicago, Ill., assignor to
Automotive Oil Power, Inc., Chicago, Ill.

Application November 19, 1936, Serial No. 111,708

15 Claims. (Cl. 123—122)

This invention is a device to gasify fuel oils or other oils of low volatility for use in conventional internal combustion engines.

It is well recognized in the internal combustion engine art that an engine designed to operate on a highly volatile fuel, such as gasoline, can also be operated at lower cost and greater comparative power and mileage efficiency on less volatile fuel, such as kerosene, furnace fuel oil, and even higher boiling point fuels, after the said engine has attained a sufficiently high temperature if other conditions requisite to the use of such higher boiling fuels are met.

The problems incident to the use of fuels of higher boiling point than gasoline seem to be that of properly carbureting the low grade fuel, of heating such carbureted fuel to proper temperature so that it will be completely burned without excessive or objectionable detonation, and the provision of means providing instant ability for the operator to change over from the use of one fuel to the other, should it be desirable so to do.

In the automotive industry, especially the freight carrying department, the lower cost of operation combined with the higher efficiency obtainable from the successful substitution of lower cost, higher boiling point fuels, is in great demand subject to meeting the further conditions affecting the so-called "human element" which plays such an important part in the operation of freight-carrying vehicles, the drivers of which are rarely, if ever, highly skilled mechanics and who, in order to adhere to the time schedules prescribed by their employers, must have their vehicles equipped with power plants that can be relied upon to give the requisite service at all times without burdening the operators with such matters as effecting adjustments or making replacements, etc., during travel, nor to be obliged to operate an appreciably greater number of levers than those to which they have become accustomed.

Apparently, in the light of absence from general use, the type of gasoline-oil consuming power plants wherein the type of fuel or mixtures of different fuels is attempted to be selected entirely automatically or partly so, have not proved practical or desirable for many assignable reasons, among which there may be assumed that cars having devices so equipped can not successfully meet the varying conditions of actual use on the road and that an appreciable degree of skill and judgment or discretion of the driver must be relied upon. It is safe to state that the lat-

ter must be reduced to the lowest possible minimum to assure economic success in the use of power plants of the type referred to. The economic factor involves maximum periods of use of the cheaper fuel, ability to instantly switch from one fuel to another under certain conditions, ability to operate the vehicle wholly on the lighter fuel if heavy fuel is not available, elimination of repairs and avoidance of loss of running time in effecting adjustments.

The present invention is designed particularly to meet the needs of the drivers of automotive vehicles of all types in the simplest manner deemed possible and the essence of which lies in the provision of means whereby an instant switch over from the use of one type of fuel to another may be effected so that the engine may operate on the more volatile fuel to the practical complete exclusion of the less volatile fuel and wherein the more volatile fuel is used in minimum proportion to the less volatile fuel when the engine is operated on the latter in order that when the vehicle is stopped the driver may instantly switch over to the more volatile fuel for engine idling purpose and for attaining an initial speeding up in travel after each stop before switching over to the use of less volatile fuel, thus to avoid delays incident to "stalling" the engine due to effecting the last-named switch-over too soon following a stop, it being obvious that by maintaining an engine-idling supply of the more volatile fuel at all times, the driver may, if he notices that the vehicle is slowing up following switching over to the less volatile fuel, switch back to the more volatile fuel before the momentum of the vehicle is lost. As every stoppage of engine operation necessitates resort to the electric-self-starter, the reduction of such stoppages to the minimum also effects an economy.

As the switch-over from one fuel to the other is effected by the manual operation of only one device, nothing is left to the discretion of the driver other than taking notice of the slowing of the vehicle following switch over to the less volatile fuel.

This device further seeks to provide a device to gasify fuel oils which will be simple in operation and which may be readily attached to a conventional engine without substantial changes of the regular parts thereof.

Among other objects this invention provides a device for gasifying fuel oils and provides at the same time means whereby the engine may be started in the regular manner on gasoline and may be readily changed over, at the option of

the operator, from operation on gasoline to operation on fuel or other less volatile oil.

Further, this invention provides a device which will enable the conventional engine to operate at high speeds on fuel oil, when the device is so set, but so made that when set to operate at higher speeds on fuel oil the engine will idle on gasoline fuel.

A still further object of the device is to provide a means to thoroughly vaporize and gasify the fuel or other oil of low volatility and prepare the same for combustion in a conventional internal combustion engine, and further, preventing the accumulation of any substantial quantities of unburned fuel within the cylinders and consequent dilution of the crank case oil.

Aside from the foregoing, it is a further object of the invention to render the structure as simple, cheap and durable as possible and to render the cost of installation of the same as low as possible, and further, to so construct and install the same as to reduce the cost of repairs and replacements to the minimum.

Other and further objects will appear from the following description of illustrated embodiments of the present invention.

On the drawings:

Fig. 1 is a side elevational view of the device attached to a conventional internal combustion engine, the device being indicated by full lines and the carburetors, intake and exhaust manifolds being indicated by broken lines.

Fig. 2 is a perspective view of the device attached to the intake and exhaust manifolds of a conventional engine, showing particularly the operating levers.

Fig. 3 is an end elevational view of the device, taken from the rearward end nearest the dash or operating board, the manually operable control rod being shown in section, and the spring which controls the relative operation of the carburetor control levers being broken at its intermediate portion to better illustrate the connection of these levers to the transversely positioned control rods.

Fig. 4 is an enlarged side elevational view of the device attached to a conventional engine, part of the main body portion being broken in section to show the position of the internal fuel passageway or flue.

Fig. 5 is a vertical central cross sectional view of the device taken on line 5—5 of Fig. 1, the arrows indicating the direction taken by the vaporized fuel in both gasoline and less volatile fuel in reaching the conventional intake manifold.

Fig. 6 is an enlarged detail drawing indicating the relative position of the carburetor operating rods which may selectively, at the option of the operator, serve to operate either the gasoline or fuel oil carburetor depending upon the relative position of the operating control rod.

Fig. 7 is a perspective view of the collars and arms, the relative positioning of which controls the selective operation of one or the other carburetors.

Fig. 8 is a side elevational view of a modified form of the body or flue portion, which is particularly adapted for engines having exhaust ports in close relative position to the flue or body portion. In this view part of the outer wall is broken away to show the inwardly extending heat collecting surface and a portion of this surface being broken to show the hollowed out internal

portion behind it and the holes allowing ingress and egress of the exhaust gases into this hollowed out internal portion.

Fig. 9 is a central vertical cross sectional view taken on the line 9—9 of Fig. 8, further illustrating the inwardly extending heat collecting surface and the manner and means for directing the exhaust gases against this section and allowing the same to return to the conventional exhaust manifold.

As shown on the drawings:

The numeral 1 is used to indicate the conventional exhaust manifold of a conventional multi-cylinder internal combustion engine, located below and in the same vertical plane as the enlarged central portion 2a of the intake manifold 2. Said exhaust manifold has a substantially flat outer wall in which an aperture is made, as later herein set out, and to which the main body portion or flue 5 may be detachably connected as hereinbelow indicated.

The numeral 2 is used to indicate the conventional engine fuel intake manifold which has, at its central portion, a substantially square enlarged section 2a, said section having a relatively large hole or aperture formed in the top wall thereof and having a substantially elliptical collar portion formed around said hole on the outer periphery of said section 2a. A plurality of threaded bolt holes formed in said elliptical collar section adapted to receive and be fastened by means of stud bolts filled in said threaded holes to the face of the elliptical collar portion formed around the lower aperture in the T-shaped section 3.

The numeral 3 is used to indicate a substantially T-shaped casting or adapter having apertures formed at the top and bottom thereof, each of said apertures having a substantially elliptical collar section, the lower collar being bolted, as above indicated, to the similarly formed collar in the intake manifold section 2a, and the upper collar being adapted to be fastened by means of stud bolts to the outlet throat of a conventional downdraft carburetor indicated by the numeral 4. A further aperture, substantially square in shape, is formed at the side of said T-shaped adapter portion 3 adapted to be fitted, as later further set out, to the main body or flue portion 50 of the device, indicated by the numeral 5.

The duct or flue portion 5 in the form shown in Figs. 1 to 5 inclusive is a perpendicularly extending hollow duct or flue having an aperture on its inner face at the uppermost part thereof adapted, as shown on the drawing, to be fitted at that point to the side aperture in the T-shaped section 3. At its lowermost part said flue portion 5 has an aperture formed therein and a collar portion formed around said aperture adapted to be fastened, as shown on the drawings, to the outlet throat of a conventional up-draft carburetor, indicated by the numeral 6.

The flue or duct portion 5 has, as shown in Figs. 4 and 5, an outwardly turned central portion indicated by the numeral 5c, which extends substantially into the exhaust manifold 1 through an aperture cut into the side of the exhaust manifold 1. A gasket, indicated by the numeral 1a prevents the exhaust gases from leaking around the body portion 5 at its point of contact with the face of the manifold 1. A plate, indicated by the numeral 5a, having an aperture therein, said aperture having a covering of mica or other non-inflammable transparent material, is bolted over

the hollow section 5b, as shown in Fig. 5, permitting visual inspection of the color of the heated metal in said inturned section 5c.

The modified form of the invention, shown in Figs. 8 and 9, dispenses with the outwardly turned U-shaped central portion 5c extending into an aperture in the exhaust manifold, and substitutes for it the inwardly positioned heating surface 5d, substantially as shown which may, if desired, be formed arcuately or parallel to the outer wall of flue or duct 5. This form is particularly adapted for use on those engines having an exhaust port or ports in registry with the flue portion. As will be apparent from Fig. 9, this heating surface 5d substantially narrows the throat of flue portion 5 so that gases passing the heating surface 5d will be raised to the required temperature. The proportions and positioning of portion 5d must, of necessity, be varied in accordance with shape of various intake and exhaust manifolds in use and with various engine capacities.

The tube 5g, having a central longitudinal passage formed therein, is placed to extend substantially into the exhaust manifold directly opposite an exhaust port in the cylinder block. A collar member or coupling 5f fastened to flue portion 5 by means of stud bolts and having a centrally formed passage therethrough, this passage connecting with aperture 5h in flue portion 5, is then fastened to the tube 5g by means of stud bolts. Gaskets are used at the points of contact of coupling 5f with the body portion 5 and with tube portion 5g and also at the point of contact of tube 5g and the outer surfaces of exhaust manifold 1, to prevent leakage of the exhaust gases.

As shown in the drawings, a further connection or coupling, indicated by the numeral 5e, serves to connect aperture 5i (Fig. 8) with a second aperture formed in exhaust manifold 1, to allow the exhaust gases collected by tube 5g and which pass through connection 5f and heat surface 5d, to be returned to the exhaust manifold 1. Connection 5e is attached to flue portion 5 and exhaust manifold 1 by means of stud bolts and gaskets are also used at the points of connection to prevent leakage of the exhaust gases.

The form of structure above set forth effectively directs the exhaust gases against the internal heating surface and is equally as effective in operation as the form shown in Fig. 5. It is obvious that on larger motors a plurality of exhaust gas collecting tubes similar in function to that indicated by numeral 5g in Fig. 9, may be employed and a plurality of exhaust outlets or one substantially larger than that illustrated, may be used.

The numeral 7 indicates a conventional electrically operated fuel pump, which is operatively connected to a source of fuel oil and which discharges into the bowl of the fuel oil carburetor 6. Said fuel pump 7 receives its impulsive energy from the conventional engine electrical system and is cut in or out of operation by the lever 8a of switch 8, shown in Figs. 1, 2 and 4 operated by rod 11, as hereinafter described.

It should further be obvious that the carburetors can be gravity fed on some types of installations or that other conventional means may be used to supply fuel to the additional carburetor forming a part of this device.

The numeral 9 indicates a horizontally slidable rod or wire which operates in a surrounding casing 9b and terminates at its rearward end in an operating button or handle 9a. The casing 9b

is fastened at its rearward end to the operating or dash board and is supported at its forward end by the bracket 10 which is rigidly fastened to the motor.

As indicated on the drawings, the slidable rod 9 terminates at its forward end in an adjustable arm or protrusion 11a which is adjustably but solidly connected to the slidable rod 11. At its rearward end rod 11 rests slidably in a guide formed in bracket 10, and is connected at its forward end to the operating lever 8a of switch 8, controlling the operation of fuel pump 7. At its intermediate section the rod 11 carries an adjustable transversely extending bolt 11b which connects to the upward extending lever 13 of the conventional foot throttle.

The numeral 12 indicates a double-ended arm or member having a slot formed therein, in which the bolt 11b is slidably positioned, and which is preferably fastened, as shown in Figs. 2, 3 and 4, at its upper central portion to the semirotatable rod or rockshaft 14, such that when rod 11 is in its most rearward position in the slot in said member 12 upward movement of throttle lever 13 will cause movement of rod or rockshaft 14 in a direction opposite to the movement imparted to said rod or rockshaft 14 when rod 11 is in its forwardmost position. As shown in Fig. 2, rod 14 is rotatably supported by the brackets 14a and 14b. Loosely fitted on rod 14, said rod 14 extending through holes in said levers, are arms, or levers 14c and 14d, respectively, which operate the rods 15 and 16 connected to the outward extending arms 17 and 18 which are operatively connected respectively to the internal butterfly valves of carburetors 4 and 6.

The arms or levers 14c and 14d are connected to said rod 14 by means of a plurality of adjustable collar members 14e. The collar members 14e have a semi-circularly extending peripheral slot formed therein and rods 14c and 14d each fit through this slot, the ends of said slot defining the movement of said arms. Collar members 14e may be adjusted on rod 14 by means of the adjustment bolt 14f, as particularly shown in Fig. 6, and are so positioned that the rotation of rod 14 in one direction will impart movement of lever 14c, allowing lever 14d to idle. Rotation of said rod 14 in the opposite direction will impart movement only to lever 14d. The coil spring 19 extending, as shown in Figs. 3 and 6, between said rods 15 and 16 serves to keep the rods in close relative operating position and effectively closing the butterfly valve in the one carburetor, while the other carburetor is functioning.

In operation the knob 9a may be pushed to its forwardmost position by the hand or foot, causing rod 11 to assume its forwardmost position in the internally formed slot in arm member 12. In this position the engine throttle will open the butterfly valve in the upper or gasoline carburetor 4. Wherever the term "manually" is used herein, it should be obvious that either hand or foot operation is intended.

The engine may then be started in conventional manner on gasoline and in this position will continuously function on gasoline fuel as long as is desired or necessary. In the position set out above the conventional throttle levers will only operate the levers and rods on the upper or gasoline carburetor, the rods and arms operating the lower or fuel oil carburetor being inoperative and held in closed position by the spring 19.

When the engine has achieved normal operating temperature the knob 9a and rod 11 connected thereto may be pulled to its rearwardmost position. In this position the bolt 11b is positioned in the forwardmost portion in the slot in arm member 12 and upward movement of throttle rod or lever 13 will rotate rod 14 in a direction opposite to the rotation imparted thereto when the bolt 11b is rearwardly positioned in the slot in arm member 12. When in this position the collar 14e which controls the movement of lever 14c contacts said lever 14c causing it and rod 15 to move opening the butterfly valve in the fuel oil carburetor 6. The rearward movement imparted to rod 11 likewise pulls the switch arm or lever 8a into operative position, causing the electric fuel pump 7 to function, delivering fuel oil to said carburetor 6.

In the form particularly illustrated by Fig. 5, the heated exhaust gases passing out through exhaust manifold 1 pass the outwardly protruding section 5c, heating it to a relatively high temperature. When carburetor 6 is in operation the fuel oil vaporized therein must pass through the hollowed internal section of the flue member 5, following a substantially U-shaped path as indicated by the arrows in Fig. 5. In following the U-shaped hollow internal section of body member 5 the gases come into contact with the heated walls of section 5c, thence through the upper portion of member 5 and pass into the conventional intake manifold section 2a and into intake manifold 2, thence to the cylinders where the explosion takes place in conventional manner.

In the modified form illustrated in Figs. 8 and 9 the gases from the exhaust port or ports are directed against the heating surface 5d, heating it to a high temperature. The exhaust gases pass upwardly as indicated by the arrow in Fig. 9 and return through coupling 5e to the exhaust manifold. The position of the tube 5g opposite the exhaust port, collects the exhaust gas at high velocity and an effective circulation of the gas is maintained.

In operation the fuel vaporized by carburetor 6 passes section 5d, is heated and thoroughly gasified thereby, just as is done by the form illustrated in Fig. 5, passes to the conventional fuel intake section 2a, into intake manifold 2 and is conventionally exploded in the cylinders of the engine.

Experience has shown that the gas thus generated is highly combustible, relatively free from carbon or other undesirable residue and that the power of the engine is increased and additional mileage per gallon of fuel may be had by the use of the lower grade fuel oils.

It is obvious that, if found desirable, the carburetors and operating levers may be so adjusted that when set for operation on fuel oil at idling speeds the engine will idle on gasoline vapor supplied by the upper carburetor and the lower carburetor can be wholly out of operation. Also, if desirable, the levers and rods may be so adjusted that not only will the engine be forced to idle on gasoline but an additional charge of gasoline vapor may be supplied the engine to enrich the fuel oil vapor when the engine is accelerating. From the foregoing it will be apparent that in the use of the invention, nothing is left to the discretion of the operator except to determine when the heated portion of the flue is hot enough to permit switchover from gasoline to

furnace oil and vice versa upon stopping the vehicle. The number of operating parts of the apparatus is reduced to a very small number which may be made sturdy enough to be extremely durable thus reducing possibilities of necessity for repairs or replacements to a very low point.

The particular objects of the invention as set forth in the statement thereof are accomplished by the particular embodiment herein illustrated and described, but it will be apparent that details of construction may be changed and varied without departing from the invention as defined in the appended claims, and I contemplate that various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. In a device to gasify fuel oil the combination of an internal combustion engine having an intake manifold and an exhaust manifold, a carburetor adapted to vaporize gasoline, a throat connection on said intake manifold, said gasoline carburetor discharging directly into said throat on said intake manifold, a carburetor adapted to vaporize fuel oil and discharging into a hollow flue, means in said flue to collect heat from said exhaust manifold, and to thereby gasify the fuel oil vaporized by said fuel oil carburetor to combustible state, said flue discharging into said throat on said intake manifold, said throat being common to both said gasoline carburetor and said flue, and manually operable, inter-acting levers connected to said carburetors adapted to selectively and intermittently control the operation of said carburetors independently of one another from a common operating means.

2. In a device to gasify fuel oils for use in internal combustion engines the combination of an intake manifold and an exhaust manifold, a carburetor adapted to vaporize gasoline operably connected to said intake manifold, a perpendicularly extending hollow flue operably connected to said intake manifold and adapted to collect heat from said exhaust manifold, a carburetor adapted to vaporize fuel oil discharging into said flue, the vaporized fuel from said fuel oil carburetor being heated by said flue in passing therethrough, a fuel pump adapted to deliver fuel to said fuel oil carburetor and operating levers adapted to selectively control the operation of said carburetors and said fuel pump.

3. In a device to gasify fuel oils for use in internal combustion engines the combination of an intake manifold and an exhaust manifold, a carburetor adapted to vaporize gasoline operably connected to said intake manifold, a perpendicularly extending hollow flue operably connected to said intake manifold and adapted to collect heat from said exhaust manifold, a carburetor adapted to vaporize fuel oil discharging into said flue, the vaporized fuel from said fuel oil carburetor being heated by said flue in passing therethrough, an electrically operated fuel pump adapted to deliver fuel to said fuel oil carburetor, and operating levers adapted to selectively control the operation of said carburetors and the control switch of said fuel pump.

4. In combination with an internal combustion engine having an intake and an exhaust manifold

- having a side aperture therein, a downdraft carburetor adapted to vaporize gasoline, said carburetor discharging into a throat, said throat operably connected to said intake manifold and 5 having a centrally positioned side aperture therein, a vertically extending hollow flue operably connected to said aperture in said throat, said flue having an inwardly extending hollow protruding section formed thereon, said protruding section extending substantially into said aperture in the exhaust manifold and adapted to absorb 10 heat from the gases in said exhaust manifold, an updraft carburetor operably connected to said flue and discharging thereinto, the vaporized fuel oil from said fuel oil carburetor being heated in passing through said flue, and a plurality of manually operable control levers adapted to allow selective and intermittent coaction of said carburetors.
20. 5. In combination with an internal combustion engine having an intake and an exhaust manifold having an aperture therein, a downdraft carburetor adapted to vaporize gasoline, said carburetor discharging into a substantially T-shaped 25 throat, said throat operably connected to said intake manifold and having a centrally positioned side aperture therein, a vertically extending hollow flue operably connected to said aperture in said throat, said flue having an inwardly extending hollow protruding section formed thereon, said protruding section extending substantially into said aperture in said exhaust manifold and adapted to absorb heat from said exhaust manifold, an up-draft carburetor operably connected to said flue and discharging thereinto, the vaporized fuel oil from said fuel oil carburetor being heated in passing through said flue, an intermittently operable fuel pump adapted to supply fuel to said fuel oil carburetor, and manually operable means to intermittently control the same, and a plurality of manually operable control levers adapted to allow selective and intermittent co-action of said carburetors.
40. 6. In combination with an internal combustion engine having an intake and an exhaust manifold, a substantially T-shaped throat having a side aperture connected to said intake manifold, a downdraft carburetor adapted to vaporize gasoline connected and discharging into said throat, a metal flue having a hollow internal section extending to said side aperture and connected thereto and opening thereinto, said flue having an inwardly turned substantially U-shaped protruding section extending into said exhaust manifold adapted to absorb heat from the gases in said manifold, said hollow internal section following the path of said inwardly protruding section, an updraft carburetor adapted to vaporize fuel oil, a fuel pump adapted to furnish oil to said carburetor, a pump control switch and said updraft carburetor discharging into said metal flue at the lower termination thereof, a plurality of carburetor control rods extending from said carburetors and terminating centrally in a plurality of selectively operable levers operating from a common central horizontally extending control rod, a double acting arm connected to said rod having a slot therein adapted to receive the end of a throttle lever, a horizontally slidable rod adapted to shift said throttle lever in said slot in said arm reversing the rotatable motion of said arm and operate a switch and terminating rearwardly in a manually operable knob affixed to said rod.
70. 7. In a charge forming apparatus the combination of a fuel oil carburetor, a flue into which said fuel oil carburetor may discharge, an inwardly bent portion in said flue forming an inset surface restricting the internal area of said flue, an integral surface portion having a pair of apertures therein forming a hollowed out portion behind said inset surface, connections between said hollowed out portion and the exhaust manifold of an internal combustion engine, said hollowed out portion being adapted to collect 10 heated exhaust fumes and discharge the same again into said exhaust manifold thereby heating said inset surface in said flue and adapting it to gasify fuel oil vaporized by said fuel oil carburetor, a relatively unheated throat forming a 15 common intake for vaporized fuel oil from said flue and vaporized gasoline from a gasoline carburetor and means for alternating the functioning of said fuel oil carburetor and said gasoline carburetor.
20. 8. In a device to gasify fuel oil the combination of a carburetor adapted to vaporize fuel oil and to discharge the vaporized fuel oil into a flue, a flue having a wall partition therein restricting the internal area thereof and forming a heat 25 collecting portion, a gas tight connection between said heat collecting portion and the exhaust manifold of an internal combustion engine, means to direct exhaust gases against said heat collecting portion and means to permit said 30 exhaust gases to return to said exhaust manifold, a throat common to said flue and a gasoline carburetor into which each may discharge said throat being connected to the intake manifold of an internal combustion engine and manually 35 operable means to intermittently and selectively operate the gasoline and fuel oil carburetors relatively independently of one another from a common operating lever.
9. In a device of the described class the combination of a gasoline carburetor and a fuel oil carburetor, a fuel oil pump and switch-over means for controlling the operation thereof, co-acting means to gasify fuel oil vaporized by said fuel oil carburetor and means for intermittently 40 and selectively controlling the operation of each of said carburetors relatively independently of one another, comprising a manually operable lever rigidly attached to a relatively transversely extending slidable rod controlling said switch-over for said fuel pump and a lever positioned in the slot of a semi-rotatable portion having such a slot therein, said semi-rotatable portion being semi-rotatable in an opposite direction when the said lever is in the forwardmost portion of said slot than when said lever is in rearwardmost position therein, a rod rigidly attached to said semi-rotatable slotted portion and semi-rotatable in opposite directions therewith, a pair of locking members on said rod, a pair of levers locked by 45 said locking members, said locking members permitting one of said levers to remain inoperative when the rod on which they are mounted is turned in one direction and the other lever to remain inoperative when said rod is turned in 50 an opposite direction, bell cranks on each of said carburetors and links connecting each of said levers to a bell crank of one of said carburetors, said construction permitting optional operation of each of said carburetors relatively independently of the other from a common point of control.
10. In combination with an internal combustion engine, an unhusked intake manifold, an exhaust manifold, a carburetor adapted to vapor- 55 60 65 70 75

ize a low boiling point fuel and to discharge its vaporized fuel directly and unheated into said intake manifold, a carburetor adapted to vaporize a fuel of higher boiling point than that vaporized by said first mentioned carburetor and adapted to discharge its vaporized fuel into a flue rigidly attached to said exhaust manifold, means common to said flue and said exhaust manifold for directing hot exhaust gases against 5 a portion of said flue, thereby heating said flue and thereby gasifying the vaporized high boiling point mixture passed therethrough, means for returning said exhaust gases to said exhaust manifold, the vaporized fuel mixture from said flue discharging into said intake manifold in an 10 intake opening common to said first carburetor and said flue and means for selectively and intermittently operating each carburetor independently of the other from a common means of control.

11. In a device to gasify fuel oil, in combination with an internal combustion engine having an unheated intake manifold and an exhaust manifold having a side aperture therein, a carburetor adapted to vaporize gasoline in communication with a normally relatively short and unheated throat common to said carburetor and a flue, said throat being in direct communication with the intake of said engine, a substantially 15 elongated flue having a tortuous internal passageway formed therein in communication with said unheated throat at one end of said flue and with a carburetor adapted to gasify fuel oil at the other end of said flue, a portion of said flue being 20 formed to extend substantially into said aperture in said exhaust manifold and be heated by the gases therein, thereby gasifying the fuel oil vaporized by said carburetor, a fuel oil carburetor, and a lever system adapted to permit selective 25 operation of each carburetor independently of the other from a common throttle lever.

12. An apparatus of the type specified including a carburetor for a highly volatile fuel, a carburetor for a less volatile fuel, separate ducts connecting said respective carburetors with the intake manifold of the engine, a portion of the duct leading from the second-named carburetor to said manifold being disposed in the path of exhaust gases of the engine, a source of supply 45 of the less volatile fuel normally disconnected from the second-named carburetor, a source of supply of the more volatile fuel permanently connected with the first-named carburetor, a manually operable control device common to both 50 said carburetors and at all times operatively connected with one and disassociated from the other of said carburetors, and a single manually operable means for selectively associating either one of said carburetors with said device and when 55 actuated to associate the said device with the second-named carburetor connecting the latter with its source of supply of fuel.

13. An apparatus of the type specified including a carburetor for a highly volatile fuel, a carburetor for a less volatile fuel, separate ducts connecting said respective carburetors with the intake manifold of the engine, a portion of the duct leading from the second-named carburetor to said manifold being disposed in the path of

exhaust gases of the engine, a source of supply of the less volatile fuel normally disconnected from the second-named carburetor, a source of supply of the more volatile fuel permanently connected with the first-named carburetor, a manually operable control device common to both said carburetors and at all times operatively connected with one and disassociated from the other of said carburetors, and a single manually operable means for selectively associating either one of said carburetors with said device and when actuated to associate the said device with the second-named carburetor connecting the latter with its source of supply of fuel, said means including a spring connected with the first-named carburetor for adjusting the same to supply no more than engine idling fuel to the engine while the second-named carburetor is connected with the engine.

14. In a device to gasify fuel oil the combination of a carburetor adapted to vaporize fuel oil, a flue, said carburetor being adapted to discharge into said flue a wall partition formed integral with said flue, said wall partition restricting the internal portion of said flue and forming a heat exchanger, an integral back wall for said heat exchanger, a gas-tight connection between said back wall and the exhaust manifold of an internal combustion engine, tube means extending into said exhaust manifold for directing exhaust gases into said heat exchanger, connection means for returning the exhaust gases to said exhaust manifold, a carburetor adapted to vaporize gasoline, a throat common to the discharge ends of both said flue and said gasoline vaporizing carburetor, said throat being connected to the intake manifold of an internal combustion engine, and manually operable means to permit selective operation of the fuel oil and gasoline carburetors independently of each other from a single operating lever.

15. In a device of the described class, the combination of a carburetor adapted to atomize fuel of high boiling point, said carburetor altered to permit its operation only when the butterfly valve 45 thereof is opened, a flue into which said carburetor may discharge, a double wall in said flue, the internal wall extending into said flue and restricting the internal portion thereof, and forming a hollowed-out portion between one 50 outer wall and the internal wall and into which exhaust gases may be directed from the exhaust manifold of an internal combustion engine to form a heat exchanger, tube means extending into the exhaust manifold of the internal combustion engine and in register with the exhaust port thereof, said tube means being in communication with said hollowed-out portion for directing exhaust gases thereto, outlet means communicating from said hollowed-out portion 55 to the exhaust manifold of the internal combustion engine to permit return of the exhaust gases to the exhaust manifold, the end of said flue opposite the carburetor aforementioned discharging the high boiling point fuel vaporized 60 thereby into the intake manifold of the internal combustion engine.

ARTHUR J. BEHLING.
